INDUSTRIAL AUTOMATIC OIL BURNER OR THE LIKE

Fredrick Mros, Jr., Salt Lake City, Utah

Application September 30, 1957, Serial No. 687,135

9 Claims. (Cl. 158—77)

This invention relates to industrial, automatic oil burners of the rotary-cup type, and more particularly to a new and improved industrial burner capable of handling up to and including number six industrial fuel oil and provided with a type of air injection in the rotary fuel cup.

Heretofore, a great number of industrial oil burners of the rotary-cup type have been developed. In the operation of conventional burners, industrial fuel oil is introduced into a rapidly spinning fuel cup. By virtue of centrifugal force imparted to the fuel oil by the rotating cup, the oil is impressed against the inner wall of the cup, taking the form of a fuel layer which progresses gradually toward the mouth of the cup as additional fuel oil is progressively introduced into the cup. A blast of air is supplied exteriorly of the cup and is directed in the same direction as that of the travel of the fuel oil layer along the inner cup wall. At a time prior to the fuel layer's reaching the mouth of the cup, an ignition flame is introduced at or near the mouth of the atomizing cup by an auxiliary burner. On reaching the mouth or lip of the cup, the fuel oil is atomized by the air blast so as to enable rapid and complete oxidation and combustion of the fuel oil upon ignition thereof by the flame of the auxiliary burner.

In the recent past, the inventor has devised an improved, industrial oil burner system which is fully automatic in its starting cycle and general operation. In this improved system, number six industrial fuel oil, for example, is pre-heated in an intermediate reservoir to about two hundred fifty degrees Fahrenheit, so as to reduce the oil's viscosity. The fuel oil is introduced into the atomizing cup of the burner by means of a valve, which valve is closed during the first portion of the starting cycle. During this first portion of the starting cycle, the pre-heated fuel oil is pumped into the intake line of the burner and (since the valve is closed) through the return line (to the intermediate reservoir) so as to purge these lines of any cold, viscous fuel oil which may have remained in the lines since the previous firing of the burner. After all old oil is purged from the aforementioned lines, a temperature sensitive control in the return line is actuated, by reason of the high temperature of the newly introduced fuel oil, so as, in turn, to actuate a blower for supplying the aforementioned air blast. Subsequently, the auxiliary burner is ignited and the fuel valve inside the atomizing cup opens, causing fuel oil to be introduced into the cup for ultimate combustion, as above explained.

While the oil burner system above described in brief is thought to be a notable advance in the industrial, oil burner art, yet, further improvement in performance of the burner can be attained by eliminating all possibility of carbon deposit or crust formation in the interior of the rotary cup which might otherwise occur—and this is true of all burners—either during normal operation of the burner or during the cooling interval immediately thereafter. Further, it would be highly desirable to prevent seepage of fuel oil introduced into the cup, rearwardly into burner apparatus bearing mounts. Additionally, it

2

would be desirable to render the fuel layer in the cup as thin as possible, so as to render atomization and combustion of the fuel oil as complete as possible.

Accordingly, it is an object of the present invention to provide a new and improved industrial burner of the rotary cup type.

It is an additional object to provide a new type rotary cup burner in which crust formation on a conventional rotary cup is avoided, both during actual operation of the burner and during the cooling period immediately following.

It is an additional object of the present invention to provide an industrial burner of the rotary-cup type in which fuel oil seepage into the bearings of the burner apparatus is avoided.

It is a still further object of the present invention to provide an industrial burner of the rotary-cup type in which atomization of fuel oil progressing outwardly of the cup is enhanced.

It is an additional object to provide an air injection, fuel valve device incorporating features accomplishing all of the foregoing objects, which device may be incorporated into any conventional, rotary cup burner.

According to the present invention, an industrial burner of the rotary-cup type is provided with means for accommodating the introduction of forced air within the atomizing cup proper, the forced air being directed generally toward the mouth or lip of the atomizing cup. The forced air keeps the atomizing cup cool during burner operation and may be left on during the cooling period of the burner so as to prevent unwanted, burnt oil-coke deposits on the interior of the cup. This air injection within the atomizing cup may be accomplished by means of a baffle perforate on the outer surface thereof, the baffle additionally serving to prevent seepage of fuel oil rearwardly into burner bearings. The baffle orifices may be so disposed that the air streams therefrom will tend to reduce the thickness of the fuel layer on the interior wall surface of the cup and to urge the fuel layer outwardly therefrom.

The features of the present invention which are believed to be novel are set forth with particularity in the appended claims. The present invention, both as to its organization and manner of operation, together with further objects and advantages thereof, may best be understood by reference to the following description, taken in connection with the accompanying drawings in which:

Figure 1 is a front elevation view of an industrial automatic oil burner according to the present invention.

Figure 2 is a side elevation of the apparatus shown in Figure 1, looking from the left side thereof.

Figure 3 is a sectional view of the apparatus, taken along the line 3—3 in Figure 2, showing with particularity the novel valve construction utilized by the present invention.

Figure 4 is a sectional view taken along the line 4—4 in Figure 3.

In the drawings:

Housing 10 is composed of a series of castings as is illustrated with particularity in Fig. 3. Housing 10 is provided with a cylindrical opening 11 into which is fitted slide tube 12, affixed to housing 10 by means of screw 13. Motor housing 14 is provided with a cylindrical opening 15, corresponding to opening 11, which is adapted to slide along slide tube 12. Motor housing 14, when butting against housing 10, is affixed in place by means of the cooperation of threaded locking screw 16 with tapered aperture 17 disposed in the wall of slide tube 12.

Disposed within motor housing 14 is an electric motor 18 which, for example, may be of the ½ hp., 3,450 r.p.m., 3 phase type. Motor 18 is provided with a ho-

low output member 19, which may be flanged, as shown in Figure 3.

Bolted to the flanged portion of motor output member 19 is an extension sleeve 20. Flange 21 is threaded into extension sleeve 20 to affix in place the outer race of bearing 22. The outer race of bearing 23 is affixed in place by means of the flanged abutment of motor output member 19. Bolted to flange 21 is a radial atomizing cup 24. Atomizing cup 24 is provided with an outwardly turned lip portion or mouth 25 and also includes a base flange 26 for bolt connection.

Extending coaxially through motor output member 19 and extension sleeve 20 is an interior sleeve 27 which provides circumferential mounts for the inner races of bearings 22 and 23. The inner race of bearing 22 is tightened in place by means of threaded ring 28. Interior sleeve 27 may be securely fitted into the motor housing and secured thereto by means of flange 29 and bolts 30.

The heart of the present invention resides in the design of the apparatus disposed interiorly of interior sleeve 27. This apparatus consists of three coaxial conduit members which are preferably tubular in conformation. These are: outer conduit member 31, intermediate member 32, and inner conduit member 33. The ends of outer conduit member 31 are flared inwardly and welded or otherwise affixed to the outer surface of intermediate member 32. The space enclosed between outer conduit member 31 and intermediate conduit member 32 is provided to supply passage for forced air introduced at air connection 34 to baffle 35.

A circumferential series of apertures 36 disposed in the wall of outer conduit member 31 provides air passage to the hollow interior of baffle 35. Outer surface 37 of baffle 35 is likewise provided with a peripheral series of air orifices 38. As is shown in Figure 3, the outer circumferential periphery of baffle 35 is disposed in close proximity with, but separated from, the interior surface of atomizing cup 24. Baffle 35 may be secured in place by means of set screw 39.

Intermediate conduit member 32 is interiorly tapered at the atomizing cup end thereof and supplies a bearing surface for plug valve 40. Plug valve 40 and inner conduit member 33 are securely affixed to each other and are provided with a lined valve port 41. Valve port 42, when the valve is open, is aligned with valve port 41.

Accordingly, it is seen that the rotational displacement of inner conduit member 33 with respect to intermediate conduit member 32 will produce selective opening and closing of the fuel valve within the atomizing cup.

Fuel oil inlet and outlet connections 43 and 44 are affixed to intermediate conduit member 32 as shown. An isolating baffle 45 is ring-shaped and is disposed between intermediate and inner conduit members 32 and 33 in a region between the inlet and outlet fuel oil connections. Apertures 46 are supplied in the wall of inner conduit member 33 in a region rearwardly of isolating baffle 45. Thus, when the valve in the atomizing cup is closed, fuel oil pumped into fuel intake connection 43 will flow in the area between the inner and intermediate conduit members to a point interior of the atomizing cup and through return ports 47 and 48 to oil outlet connection 44. When the valve is open in the atomizing cup, then a portion of the fuel oil so pumped into the lines will pass into the spinning atomizing cup. The centrifugal force imparted to the fuel oil introduced into the atomizing cup by the cup itself will cause the fuel oil to produce a fuel layer along the inner surface of the atomizing cup, which layer will gradually progress toward the mouth of the atomizing cup as additional fuel oil is introduced therein.

Forced air is introduced by means of a blower into housing 10, which is directed, ultimately, toward the outer surface of the cup and beyond. Accordingly, when the fuel layer reaches the lip or mouth of the atomizing cup, the fuel oil will be atomized by the air blast at the mouth

of the cup so as to insure complete oxidation and combustion of the fuel.

The purpose of the baffle 35 and the air supplying means accommodating the same is to inject a plurality of small air streams within the atomizing cup. This air stream plurality serves a number of purposes. In the first place, these air streams tend to keep the atomizing cup cool during normal burner operation so as to prevent crust formation of oil-coke deposits. It is desirous that these baffle air streams be maintained during the cooling period of the burner so as to force residual fuel oil out of the cup and to prevent the aforementioned crust formation.

In the absence of a baffle, it has been found that, notwithstanding the spinning and taper of the atomizing cup, some seepage of fuel oil into the bearings 22 and 23 will take place. However, by virtue of the thickness of flange 21 and the design of baffle 35 itself, rearward seepage of fuel oil is avoided.

The air streams from baffle 35 also serve to reduce the thickness of the fuel layer progressing toward the mouth of atomizing cup 24, so as to optimize atomization of the fuel oil upon its reaching the mouth of the cup.

The present design includes a drip-oiler connection 49 for supplying lubricating oil to the bearings 22 and 23 by means of lubricating oil passage 50 and lubricating oil outlet 51.

The intermediate and inner conduit members 32 and 33 are fitted into casing 52 as shown. The plug valve 40 is retained in place by means of loading spring 53 and the abutment of the same against packing washers 54 and sleeve abutment 55. Jam nuts 56 secure the rear assembly. It will be noted that the inner conduit member 33 is keyed into the rear assembly 57 so that rotation of shaft 58 by linkage 59 will produce the rotation of plug valve 40 and inner conduit member 33 with respect to intermediate conduit member 32.

Linkage 59 is coupled to control motor 60, the conventional design of which enables the rotational displacement of the output shaft thereof upon suitable energization.

While particular embodiments of the present invention have been shown and described, it will be obvious to those skilled in the art that changes and modifications may be made without departing from this invention in its broader aspects, and, therefore, the aim in the appended claims is to cover all such changes and modifications as fall within the true spirit and scope of this invention.

I claim:

- Industrial burner apparatus of the rotary, atomizing cup type including, in combination, a motor having an axially rotatable, hollow, output member; an atomizing cup mechanically coupled to said motor output member to rotate therewith; coaxially aligned and radially separated, outer, intermediate, and inner conduit members closed at both ends and coaxially disposed within and through said motor output member; each of said conduit members having one end portion extending within said atomizing cup and the remaining end portion extending beyond said motor output member in a direction away from said atomizing cup; said outer conduit member being mechanically separate from said motor output member; said outer conduit member defining a generally enclosed airspace adjacent the outer surface of said intermediate conduit member, having an air-intake connection in the region of said remaining end portion, and being provided with a series of apertures circumferentially disposed in the region of said one end portion; a laterally disposed, hollow baffle affixed to said outer conduit member, near the base of said cup, in registry with said circumferentially disposed apertures, and provided with a series of air outlet orifices directed outwardly of said cup; said intermediate conduit member having a valve port

disposed in said one end portion and fuel intake and outlet connections disposed on said remaining end portion; an isolation baffle disposed between said intake and outlet connections and between said intermediate and inner conduit members; said inner conduit member being provided with at least one aperture in the region beyond said baffle (farthest removed from said cup); said one end portion of said inner member being provided with at least one aperture for rendering flow connection between the area between said intermediate and inner conduit members and the interior of said inner conduit member; said one end portion of said inner member also being provided with a valve port selectively alignable with said intermediate member valve port; and said inner conduit member being rotationally displaceable with respect to said intermediate conduit member.

2. Apparatus according to claim 1 in which the circumferential periphery of said laterally disposed hollow baffle is in proximity with but physically separate from said cup, and in which said outwardly directed baffle orifices are in proximity with said periphery of said baffle.

3. Industrial burner apparatus of the rotary, atomizing cup type including, in combination, a motor having a housing and an axially rotatable, hollow, output member; an extension sleeve affixed to said motor output member; a flange affixed to said extension sleeve; an atomizing cup affixed to said flange; an interior sleeve affixed to said housing and bearinged within said extension sleeve; and a fuel valve, air injection device comprising: coaxially aligned and radially separated, outer, intermediate, and inner conduit members closed at both ends and coaxially disposed within and through said interior sleeve; each of said conduit members having one end portion extending within said atomizing cup and the remaining end portion extending beyond said interior sleeve in a direction away from said atomizing cup; said outer conduit member defining a generally enclosed air-space adjacent the outer surface of said intermediate conduit member, having an air-intake connection in the region of said remaining end portion, and being provided with a series of apertures circumferentially disposed in the region of said one end portion; a laterally disposed, hollow baffle affixed to said outer conduit member, near the base of said cup and in front of said flange, in registry with said circumferentially disposed apertures, and provided with a series of air outlet orifices directed outwardly of said cup; said intermediate conduit member having a valve port disposed in said one end portion and fuel intake and outlet connections disposed on said remaining end portion; an isolation baffle disposed between said intake and outlet connections and between said intermediate and inner conduit members; said inner conduit member being provided with at least one aperture in the region beyond said baffle (farthest removed from said cup); said one end portion of said inner member being provided with at least one aperture for rendering flow connection between the area between said intermediate and inner conduit members and the interior of said inner conduit member; said one end portion of said inner member also being provided with a valve port selectively alignable with said intermediate member valve port; and said inner conduit member being rotationally displaceable with respect to said intermediate conduit member.

4. Industrial burner apparatus of the rotary, atomizing cup type including, in combination, a motor having a housing and an axially rotatable, hollow, output member; an extension sleeve affixed to said motor output member; a flange affixed to said extension sleeve; an atomizing cup affixed to said flange; an interior sleeve affixed to said housing and bearinged within said extension sleeve; and a fuel valve, air injection device comprising: coaxially aligned and radially separated, outer, intermediate, and inner conduit members closed at both ends and coaxially disposed within and through said interior sleeve; each of said conduit members having one end portion extending

within said atomizing cup and the remaining end portion extending beyond said interior sleeve in a direction away from said atomizing cup; said outer conduit member having a clearance with respect to said interior sleeve of the order of .005 inch; means for terminating said clearance at the termination of said sleeve farthest removed from said cup, said clearance defining a bearing lubrication fluid passage; lubricating fluid connection means provided said interior sleeve; a lubricating oil outlet orifice disposed in said interior sleeve in the region of said extension sleeve; said outer conduit member defining a generally enclosed air-space adjacent the outer surface of said intermediate conduit member, having an air-intake connection in the region of said remaining end portion, and being provided with a series of apertures circumferentially disposed in the region of said one end portion; a laterally disposed, hollow baffle affixed to said outer conduit member, near the base of said cup and in front of said flange, in registry with said circumferentially disposed apertures, and provided with a series of air outlet orifices directed outwardly of said cup; said intermediate conduit member having a valve port disposed in said one end portion and fuel intake and outlet connections disposed on said remaining end portion; an isolation baffle disposed between said intake and outlet connections and between said intermediate and inner conduit members; said inner conduit member being provided with at least one aperture in the region beyond said baffle (farthest removed from said cup); said one end portion of said inner member also being provided with a valve port selectively alignable with said intermediate member valve port; and said inner conduit member being rotationally displaceable with respect to said intermediate conduit member.

5. In industrial burner apparatus of the rotary, atomizing cup type including a motor having a housing and an axially rotatable, hollow, output member, an extension sleeve affixed to said motor output member, a flange affixed to said extension sleeve, an atomizing cup affixed to said flange, an interior sleeve affixed to said housing and bearinged within said extension sleeve; an improved fuel valve, air injection device, said device comprising: coaxially aligned and radially separated, outer, intermediate, and inner conduit members closed at both ends and coaxially disposed within and through said interior sleeve; each of said conduit members having one end portion extending within said atomizing cup and the remaining end portion extending beyond said interior sleeve in a direction away from said atomizing cup; said outer conduit member defining a generally enclosed air-space adjacent the outer surface of said intermediate conduit member, having an air-intake connection in the region of said remaining end portion, and being provided with a series of apertures circumferentially disposed in the region of said one end portion; a laterally disposed, hollow baffle affixed to said outer conduit member, near the base of said cup and in front of said flange, in registry with said circumferentially disposed apertures, and provided with a series of air outlet orifices directed outwardly of said cup; said intermediate conduit member having a valve port disposed in said one end portion and fuel intake and outlet connections disposed on said remaining end portion; an isolation baffle disposed between said intake and outlet connections and between said intermediate and inner conduit members; said inner conduit member being provided with at least one aperture in the region beyond said baffle (farthest removed from said cup); said one end portion of said inner member also being provided with a valve port selectively alignable with said intermediate member valve port; and said inner conduit member being rotationally displaceable with respect to said intermediate conduit member.

selectively alignable with said intermediate member valve port; and said inner conduit member being rotationally displaceable with respect to said intermediate conduit member.

6. In industrial burner apparatus of the rotary, atomizing cup type including a motor having a housing and an axially rotatable, hollow, output member, an extension sleeve affixed to said motor output member, a flange affixed to said extension sleeve, an atomizing cup affixed to said flange, an interior sleeve affixed to said housing and bearinged within said extension sleeve; an improved fuel valve, air injection device, said device comprising: coaxially aligned and radially separated, outer, intermediate, and inner conduit members closed at both ends and coaxially disposed within and through said interior sleeve; each of said conduit members having one end portion extending within said atomizing cup and the remaining end portion extending beyond said interior sleeve in a direction away from said atomizing cup; said outer conduit member having a clearance with respect to said interior sleeve of the order of .005 inch; means for terminating said clearance at the termination of said sleeve farthest removed from said cup, said clearance defining a bearing lubrication fluid passage; lubricating fluid connection means provided said interior sleeve; a lubricating oil outlet orifice disposed in said interior sleeve in the region of said extension sleeve; said outer conduit member defining a generally enclosed air-space adjacent the outer surface of said intermediate conduit member, having an air-intake connection in the region of said remaining end portion, and being provided with a series of apertures circumferentially disposed in the region of said one end portion; a laterally disposed, hollow baffle affixed to said outer conduit member, near the base of said cup and in front of said flange, in registry with said circumferentially disposed apertures, and provided with a series of air outlet orifices directed outwardly of said cup; said intermediate conduit member having a valve port disposed in said one end portion and fuel intake and outlet connections disposed on said remaining end portion; an isolation baffle disposed between said intake and outlet connections and between said intermediate and inner conduit members; said inner conduit member being provided with at least one aperture in the region beyond said baffle (farthest removed from said cup); said one end portion of said inner member being provided with at least one aperture for rendering flow connection between the area between said intermediate and inner conduit members and the interior of said inner conduit member; said one end portion of said inner member also being provided with a valve port selectively alignable with said intermediate member valve port; and said inner conduit member being rotationally displaceable with respect to said intermediate conduit member.

7. Industrial burner apparatus of the rotary, atomizing cup type including, in combination, a motor having an axially rotatable, hollow, output member; an atomizing cup mechanically coupled to said motor output member to rotate therewith; means for directing forced air against the exterior and outwardly of said cup; coaxially aligned and radially separated, outer, intermediate, and inner conduit members closed at both ends and coaxially disposed within and through said motor output member; each of said conduit members having one end portion extending within said atomizing cup and the remaining end portion extending beyond said motor output member in a direction away from said atomizing cup; said outer conduit member being mechanically separate from said motor output member; said outer conduit member defining a generally enclosed air-space adjacent the outer surface of said intermediate conduit member, having an air-intake connection in the region of said remaining end portion, and being provided with a series of apertures circumferentially disposed in the region of said one end portion; a laterally disposed, hollow baffle

affixed to said outer conduit member, near the base of said cup, in registry with said circumferentially disposed apertures; and provided with a series of air outlet orifices directed outwardly of said cup; said intermediate conduit member having a valve port disposed in said one end portion and fuel intake and outlet connections disposed on said remaining end portion; an isolation baffle disposed between said intake and outlet connections and between said intermediate and inner conduit members; said inner conduit member being provided with at least one aperture in the region beyond said baffle (farthest removed from said cup); said one end portion of said inner member being provided with at least one aperture for rendering flow connection between the area between said intermediate and inner conduit members and the interior of said inner conduit member; said one end portion of said inner member also being provided with a valve port selectively alignable with said intermediate member valve port; and said inner conduit member being rotationally displaceable with respect to said intermediate conduit member.

8. Industrial burner apparatus of the rotary, atomizing cup type including, in combination, a motor having a housing and an axially rotatable, hollow, output member; an extension sleeve affixed to said motor output member; a flange affixed to said extension sleeve; an atomizing cup affixed to said flange; means for directing forced air against the exterior and outwardly of said cup; an interior sleeve affixed to said housing and bearinged within said extension sleeve; and a fuel valve, air injection device comprising: coaxially aligned and radially separated, outer, intermediate, and inner conduit members closed at both ends and coaxially disposed within and through said interior sleeve; each of said conduit members having one end portion extending within said atomizing cup and the remaining end portion extending beyond said interior sleeve in a direction away from said atomizing cup; said outer conduit member defining a generally enclosed air-space adjacent the outer surface of said intermediate conduit member, having an air-intake connection in the region of said remaining end portion, and being provided with a series of apertures circumferentially disposed in the region of said one end portion; a laterally disposed, hollow baffle affixed to said outer conduit member, near the base of said cup and in front of said flange, in registry with said circumferentially disposed apertures, and provided with a series of air outlet orifices directed outwardly of said cup; said intermediate conduit member having a valve port disposed in said one end portion and fuel intake and outlet connections disposed on said remaining end portion; an isolation baffle disposed between said intake and outlet connections and between said intermediate and inner conduit members; said inner conduit member being provided with at least one aperture in the region beyond said baffle (farthest removed from said cup); said one end portion of said inner member being provided with at least one aperture for rendering flow connection between the area between said intermediate and inner conduit members and the interior of said inner conduit member; said one end portion of said inner member also being provided with a valve port selectively alignable with said intermediate member valve port; and said inner conduit member being rotationally displaceable with respect to said intermediate conduit member.

9. Industrial burner apparatus of the rotary, atomizing cup type including, in combination, a motor having an axially rotatable, hollow, output member; an atomizing cup mechanically coupled to said motor output member to rotate therewith; coaxially aligned and radially separated, outer, intermediate, and inner conduit members coaxially disposed within and through said motor output member; each of said conduit members having one end portion extending within said atomizing cup and the remaining end portion extending beyond said motor out-

put member in a direction away from said atomizing cup; said outer conduit member being mechanically separate from said motor output member; said outer conduit member defining a generally enclosed air-space adjacent the outer surface of said intermediate conduit member, having an air-intake connection in the region of said remaining end portion, and being provided with a series of apertures circumferentially disposed in the region of said one end portion; a laterally disposed, hollow baffle affixed to said outer conduit member, near the base of said cup, in registry with said circumferentially disposed apertures, and provided with a series of air outlet orifices directed outwardly of said cup; said intermediate conduit member having a valve port disposed in said one end portion and fuel intake and outlet connections disposed on said remaining end portion; said one end portion of said intermediate conduit member having an interior taper in the region of said valve port; an isolation baffle disposed between said intake and outlet connections and between said intermediate and inner conduit members; said inner conduit member being provided with at least one aperture in the region beyond said baffle (farthest removed from said cup); said one end portion

10
5

of said inner member being provided with at least one aperture for rendering flow connection between the area between said intermediate and inner conduit members and the interior of said inner conduit member; said one end portion of said inner member also being provided with a valve port selectively alignable with said intermediate member valve port; a plug valve disposed over said one end of said inner conduit member, having a valve aperture aligned with said valve port of said inner conduit member, and having a tapered exterior cooperating with said interior taper of said intermediate conduit member; and said inner conduit member being rotationally displaceable with respect to said intermediate conduit member.
